DESIGN FOR A PORTABLE HAND FIRE EXTINGUISHER

Charles K. Huthsing, Clayton, Mo.

Application March 30, 1934, Serial No. 51,259

Term of patent 7 years

To all whom it may concern:

Be it known that I, CHARLES K. HUTHSING, a citizen of the United States and a resident of Clayton, St. Louis County, Missouri, have invented a new, original, and ornamental Design for a Portable Hand Fire Extinguisher, of which the following is a specification, reference being had to the accompanying drawing, forming part hereof, in which

Fig. 1 is a front elevation of a portable hand fire extinguisher showing my new design;

Fig. 2 is a side elevation; and
Fig. 3 is a top plan view.

I claim:

The ornamental design for a portable hand fire extinguisher, substantially as shown.

In testimony whereof, I have signed my name to this specification this 26th day of March, 1934.

CHARLES K. HUTHSING.
